NAIL MACHINE AND THE LIKE AND CONTROL APPARATUS ASSOCIATED THEREWITH

George N. Williams, Kokomo, Ind., assignor to
Continental Steel Corporation, Kokomo, Ind., a
corporation of Indiana

Application March 11, 1933, Serial No. 660,433

3 Claims. (Cl. 10—44)

This invention relates to improvements in the method of operating nail machines and the like and control apparatus associated therewith.

One object of the invention is to provide a nail machine, staple machine, or a heading machine such as would be used for bolts, screw blanks and the like, with means for continuously carrying the product from the machine.

Another object of the invention is to provide means for compulsory inspection of the product manufactured by the machine.

A further object of the invention is the provision of a means for automatically stopping the operation of such a machine when inspection of the product is not made at suitable intervals.

A further object of the invention is to provide means for inspecting and handling the products from nail machines and the like, in such a manner that one operator may tend more machines than is now possible.

A still further object of the invention is to provide means for continuous operation of such machines.

My invention applies to any cold heading and/or forming machine, adapted to have wires, strip or the like supplied thereto. In the description which follows and also in the accompanying drawings forming a part of the description I have elected to show the use of my invention in combination with a nail machine.

In order to more fully understand the invention, reference is made to the accompanying drawings, in which:

Figure 1 is a side elevational view of my entire apparatus, shown associated with the delivery end of a nail machine (in dotted lines) and a movable hopper for carrying off the finished product, (shown by the dotted lines at the end opposite the nail machine).

Figure 2 is an enlarged detailed elevational view of parts appearing in Figure 1, certain parts being broken away and shown in cross-section to facilitate description.

Figure 3 is an enlarged detailed elevational view, similar to that shown in Figure 2, the difference being, that in Figure 2, the off-bearing conveyor and automatic control are shown in their operating positions and in Figure 3, shown in their inoperative positions prior to re-setting, the dotted lines indicating the position of the nail receiving receptacle when the finished products are discharged therefrom by the machine attendant.

Figure 4 is a fragmentary detailed view as the

same would appear as taken in line 4—4, Figure 2.

Figure 5 is a fragmentary plan view as the same would appear along line 5—5 looking in the direction of the arrows, see Figure 2.

Figure 6 is an elevational view as viewed along the line 6—6 looking in the direction of the arrows, see Figure 5.

Figure 7 is a fragmentary elevational view as the same would appear if taken on line 7—7, see Figure 5.

Figure 8 is a sectional view taken on line 8—8, see Figure 3.

Figure 9 is an enlarged elevational view taken on line 9—9, Figure 1, looking in the direction of the arrows, the shifter being shown with the nail machine in its operating position.

Figure 10 is an enlarged elevational view, similar to Figure 9, the shifter being shown with the nail machine in its inoperative position.

Figure 11 is a top plan view of parts shown in Figure 10.

Like characters of reference denote corresponding parts throughout the figures.

Frame structure

80

The frame structure includes preferably the spaced end supports or beams 1 and 2 tied together at their tops by cross-member 3. Secured to the upper part of beam 1, by bolts 4, is transverse member 5, to which is rigidly attached, by means of bolts 6, the member 7. Secured to nail machine 8, by means of bolts 9 and 10 are vertical supporting members 11 and 12 respectively.

Wire reels

85

The wire reels 13 and 14, are fully described in a separate application filed of even date herewith. The wire W, is shown in the drawing, Figure 1, being drawn to nail machine 8, from reel 13, while on reel 14 the wire remains dormant. The wire is drawn from the reel 13 by a standard nail machine feed, not shown, the wire passing upwardly from reel 13 and over pulley 15 set in swivel 16 attached to cross-member 3. From pulley 15 the wire passes under pulley 17, and then into the wire feeding mechanism of the nail machine.

90

The wire reels 13 and 14 function to continuously furnish wire to nail machine 8 as follows: At the beginning of the operation, both reels are filled with wire, consisting preferably of several bundles of wire welded end to end, the back end of the bottom bundle of wire on reel 13 being welded to the front end of the top bundle of reel 14, or vice versa, as operations proceed.

95

100

105

110

As the wire is taken from reel 13, the adjustable arm 18, of reel 13, traveling in a circumferential manner around said reel, causes the wire to be removed therefrom in a uniform manner. As soon as the last coil of wire is taken from said reel, the wire automatically shifts to arm 19 of reel 14, and the machine attendant then places more wire on reel 13. It is intended to carry enough wire on each reel to supply the nail machine long enough so that sufficient time is always available for the machine attendant to place more wire on one reel, while the wire on the other reel is being supplied to the nail machine, thus securing continuous operation of the nail machine insofar as the wire supply is concerned.

Conveyor

The conveyor 20 consists of an endless belt 21 passing around roller 22 at its upper end and roller 23 at its lower end. Roller 22 is carried on shaft 24 supported in bearings 25 and 26 secured to frame members 1 and 7 respectively, by means of bolts 27 and 28 as shown in Figure 6, the lower end of said conveyor being carried on shaft 29 journaled in bearings 30 supported on brackets 31 secured to the floor by means of bolts 32. Said belt conveyor 20 is divided into sections 33 by means of angle flights 34 attached to conveyor belt 21 by means of rivets 36. Extending beneath and along the sides of belt 21 and flights 34, on the nail carrying side of said conveyor, is the guide 37 extending partially around roller 22 in order to guide the flow of the nails 38 into pan 39. At one end of shaft 24, and keyed thereto, is driving pulley 40 driven by means of belt 41 from a main line shaft not shown.

The nails passing through the chute of nail machine 8, drop on the conveyor 20 which carries said nails forward, the flights 34 preventing the nails from sliding back towards the nail machine. When the nails are carried to a point just beyond the top of the roller 22 they are discharged by gravity into the pan 39, best seen in Figure 2.

Nail receiving receptacle and co-acting mechanism

Pan 39 is supported by cylindrical lugs 42 and 43, the latter being set in open slots formed in levers 44 and 45, which are rigidly, but adjustably attached to shaft 47, in bearings 48 secured to frame member 1 by bolts 49. Attached also to shaft 47 is lever arm 50 having secured thereto, by means of bolts 51, finger 52. Secured to lever arm 50 is counterweight 53 adapted to be moved to any desired position along lever arm 50 by means of adjusting and holding screws 54. Nail receiving receptacle, or pan, 39 is so arranged that as the nails fall into said pan from conveyor 20 they may be inspected at any time by the machine attendant, who then tilts said pan, by means of handle 55, causing said nails to drop on guide 56 and into a movable hopper 57, best seen in Figure 3. If the nails are not inspected by the attendant then pan 39 remains in its receiving position, shown in Figure 2, until such time as the weight of nails in said pan overcomes the weight of the counterbalance 53. In the latter event pan 39 drops to the position shown in solid lines in Figure 3 and in dropping to this position causes lever arms 44 and 45 to move downwardly thus causing shaft 47 to revolve which, in turn, raises lever 50 to the position shown in Figure 3. As lever arm 50 raises, finger 52 also raises, engaging lug 58 secured to shaft 59, causing said shaft to make a partial rotation. Shaft 59 is supported at one

end in bearing 60 secured to frame 1 by means of bolts 61, and at its opposite end by bearing 62 formed in frame support 11. Adjustably secured to nail machine end of shaft 59, is one end of arm 63, the other end of said arm having attached thereto tension spring 64, the latter being anchored at its opposite end by bolt 64 secured in support 11. Secured also to shaft 59 and adapted to move therewith is crank 66, connected to link 68 at bearing 69. Connected also to link 68 at its opposite end at bearing 70 is belt shifting lever 71 set in guide 72, attached to supporting member 12. Secured also to support 12 and guide 72 is lever 73 having attached thereto handle 74, said lever 73 being adjustably attached to arm 75 by means of link 76, and said arm 75 being attached to belt shifting lever 71 by means of bolt 77.

Consequently, when pan 39 is caused to drop by the weight of nails therein, as has been described, and causes shaft 59 to partially rotate, said rotation causes the belt shifting mechanism to function and stop said nail machine.

With pan 39 in its receiving position as shown in Figure 2 the belt shifting mechanism of said nail machine, has its various elements arranged as shown in Figure 9. As the shaft 59 turns, arm 63 moves to a position preventing a return movement of shaft 59, and is held in this position by spring 64 until released by the machine attendant as will be described. The turning of shaft 59 also moves crank 66, link 68 and belt shifting lever 71 to the position shown in Figure 10, thus causing belt 78 to shift to the idler pulley of the nail machine 8 and stop said machine.

At the same time that these operations take place, the movement of belt shifter 71 causes lever 75 to move forward which, acting through link 76, causes arm 73 to move into an inoperative position. In the meantime spring 64 holds lever 63 and shaft 59 in a non-operative position, thus making it impossible to start the nail machine from the pan end of the apparatus.

Consequently, it is necessary for the attendant to remove the nails from pan 39, this causing counterbalance 53 through shaft 47 to move arms 44 and 45 and pan 39 into its original receiving position, and also moves finger 52 out of contact with lug 58. The attendant then shifts belt 78 to the nail machine operating pulley through movement of lever 73 by means of handle 74 thus moving shifting arm 71, link 68, crank 66 and lever 63 into the position shown in Figure 9, whereupon the machine again begins operation.

As shown in the drawings Figure 1, wire W is removed in a substantially vertical direction over pulley 15 and then passed downwardly under pulley 17 and into the nail machine 8. The nails discharged from the nail machine, instead of passing directly into a pan, or box, drop on conveyor 20 by which they are carried to pan 39 as partially shown in Figure 2. When the attendant inspects the nails at proper intervals he tilts pan 39 to the position shown by the dotted lines in Figure 3, thus discharging the nails into buggy 57, without interfering with the machine operation.

If, however, the attendant does not inspect the nails before a pre-determined weight of nails accumulates in pan 39, this weight being regulated by the setting of the counterweight 53, then the excess weight of the nails causes pan 39 to drop, which, in turn, depresses levers 44 and 45, and the latter working through shaft 47 raises lever arm 50 thus causing finger 52 to

engage lug 58 of shaft 59. Attached to the opposite end of said shaft 59 is crank 66 which, working through link 68 and belt shifter arm 71, causes belt 78 to shift to the idling pulley of the 5 nail machine, (shown in dotted lines in Figure 10) and so shuts the machine down.

In order to again start the machine, it is necessary for the attendant to discharge the nails from pan 39 into buggy 57, raise the pan 39 and 10 operating mechanisms to the position shown in Figure 2, and then by means of handle 74 to move lever 75 and cause belt shifter 71, link 68 and crank 66 to move back into their respective operating positions.

15 What I claim is:

1. In combination, a nail machine, an endless conveyor traveling inside of guides on its conveying side, and having flights adapted to form conveying pockets associated therewith, said conveying means being adapted to continuously receive products from said nail machine at one of its ends, and discharge said products at its opposite end into a holding receptacle positioned by a counter-balanced support, the latter adapted to move into another position when overbalanced causing an arm associated therewith to impart rotative movement to a shaft, causing movement of lever mechanisms adapted to move the driving belt of said nail machine from an operating position to an idling position, thus causing said machine to stop until again engaged by re-shifting said belt, substantially as described.

35

40

45

50

55

60

65

70

75

2. In a nail machine or the like, in combination, means for continuously supplying wire to said machine, means for continuously conducting the finished product from said machine, container means for receiving said products from said conducting means and holding said products until manually emptied therefrom, and means associated with said holding means for stopping the operation of said machine when a predetermined amount of said products has been received by said holding means.

3. In a machine, in combination, means for supplying material to said machine, means for receiving products produced by said machine and conveying said products from said machine, a combined receiving and holding means adapted to receive and hold said products from said conveying means, means associated with said receiving and holding means adapted by manual operation to empty said products from said receiving and holding means without stopping said machine and before a predetermined amount of product has been received thereby, means associated with said receiving and holding means for automatically stopping the operation of said machine when a predetermined amount of product has been received and held by said receiving and holding means, and means for manually resetting said receiving and holding means to its first operative position after manually emptying said held products.

GEORGE N. WILLIAMS.
